WELL BIT

Max A. Newton, Avenal, Calif.

Application October 8, 1940, Serial No. 360,271

13 Claims. (Cl. 255—61)

This invention relates to a drilling tool and relates more particularly to a bit for use in the rotary method of well drilling. A general object of this invention is to provide a practical, effective, long wearing well bit.

Another object of this invention is to provide an improved rotary well drilling bit embodying a primary set of cutting parts which are initially active in the drilling operation, and a secondary set of cutting parts which become effective or active in the drilling of the well when the primary cutting parts are worn to a given extent.

Another object of this invention is to provide a well drilling bit of the drag type in which sets or series of cutting blades are successively and automatically made operative without withdrawing the bit from the well. In the drilling of deep wells the bit is secured to the lower end of a drilling string made up of a large number of pipe sections and the string is rotated and fed downwardly so that the bit drills away the earth formation. The cutting parts of a typical rotary drag type wear away very rapidly and the bit must be removed from the well for replacement by a new or reconditioned tool after only a short period of use. The removal of the worn bit necessitates the withdrawal and disconnection of the long string of drill pipe and the insertion of the new bit requires the assembling and lowering of the pipe string into the well, which operations are tedious and time consuming. The improved bit of the present invention embodying sets of cutting parts which are successively made operative, has a much longer effective life than a typical bit and, therefore, appreciably reduces the time and labor involved in pulling and running in the drilling string.

Another object of this invention is to provide a well drilling bit embodying cutting parts fixed to the bit body and preliminary or primary cutting parts shiftable relative to the body and dependably held in active positions where they extend downwardly beyond the fixed cutting parts to be active in the drilling operation until worn dull, whereupon they are released to move up so that the fixed blades come into play to continue the drilling operation. The bit of the present invention is characterized by the preliminary cutting parts which are initially held fixed to the body until worn away to a given extent at which time they are automatically freed to retract from the well bottom thus conditioning the rigid blades to carry on the drilling operation.

Another object of the invention is to provide a well drilling bit of the character referred to which maintains the diameter or gauge of the well bore throughout the operation of both sets of cutting blades.

Another object of this invention is to provide a well bit of the character referred to that is simple and sturdy in construction and which is devoid of springs, latches, plungers, and other devices liable to fail or become inoperative.

A further object of this invention is to provide a well bit of the character referred to that is inexpensive and that is adapted to be easily and inexpensively reconditioned after use.

15 The various objects and features of my invention will be fully understood from the following detailed description of typical preferred forms and applications of my invention, throughout which description reference is made to the accompanying drawing, in which:

Fig. 1 is a side elevation of the improved bit provided by this invention. Fig. 2 is a bottom view of the bit. Fig. 3 is an enlarged fragmentary horizontal detailed sectional view taken as indicated by line 3—3 on Fig. 1. Fig. 4 is an enlarged vertical detailed sectional view taken as indicated by line 4—4 on Fig. 1, and Figs. 5 and 6 are fragmentary vertical detailed sectional views illustrating alternative means for releasably retaining the shiftable blades in their active positions.

The present invention is capable of embodiment in well drilling tools varying greatly in design and intended use. In the drawing I have illustrated the features of the invention employed in a typical embodiment, it being understood that the invention is not to be construed as limited or restricted to the specific form and application of the invention herein disclosed.

40 While I have shown the invention embodied in a bit for cutting a full diameter bore it is to be understood that the invention may be embodied in core drills, pilot bits, etc. and where I herein employ the "bit" it is to be understood as meaning any well drilling tool useful in cutting away the earth formation.

The well bit provided by this invention may be said to comprise, generally a body 10, spaced wings or cutting blades 11 rigid with the body 10, shiftable cutting blades 12, and means 13 for holding the shiftable blades 12 extended to act on the earth formation and releasable when the blades 12 are worn away to a given extent.

The body 10 is adapted to be connected with 55 the lower end of a rotary well drilling string

and is provided with suitable means for facilitating its connection with the string. In the typical case illustrated a box 14 is provided on the upper end of the body 10 to receive a tapered threaded pin of the drilling string or drill collar. It is to be understood that the body 10 may be otherwise equipped for connection with the drilling string. The major portion of the body 10 is an elongate cylindrical element whose lower end is suitably rounded or curved. A central longitudinal opening 15 extends into the body 10 from its upper end to receive the circulating fluid. It will be observed that the body 10 may be of simple sturdy design.

The wings or cutting parts 11 serve to carry the shiftable blades 12 and operate to form the outer part of the well and to cut the bore to gauge when the shiftable blades 12 are worn and the means 13 is released. There is preferably a plurality of circumferentially spaced blades 11. In the particular case illustrated there are three equally spaced blades 11 of identical or like design. In accordance with the invention the blades 11 are fixed to or rigid with the body 10. The blades 11 may be integral parts of the body 10 as illustrated, or may be secured to the body by welding, by bolts, or the like. The fixed blades 11 are elongate vertically extending parts which project downwardly and outwardly from the body 10. The blades 11 may extend throughout the major portion of the body 10 and preferably project a substantial distance downwardly from the body. The forward faces 16 of the blades 11 are flat and may lie in vertical planes which are radial relative to the central vertical axis of the bit. The blades 11 are preferably quite thick and their outer rear corners are bevelled off as at 17. The outer edges 18 of the blades 11 may be substantially vertical and serve to guide the bit and to maintain the full gauge of the bit. The lower ends of the blades 11 are bevelled off at their rear sides leaving cutting edges 19. The cutting edges 19 may be straight and horizontal and are preferably of equal extent. The fixed cutting blades 11 are preferably hard-faced throughout their wear taking parts, said parts being provided with inserts of hard wear resisting material.

The shiftable blades 12 are the initial or preliminary cutting elements acting to cut the major outer portion of the well bore until worn to a given extent, at which time they retract to expose the fixed blades 11 for operation. The shiftable blades 12 are preferably, though not necessarily, associated with the fixed blades 11. In the preferred construction the blades 12 are flat plate-like parts having broadened lower portions and upwardly extending stems 20 of reduced width. The blades 12 are arranged to lie against the forward faces of the fixed blades 11. The flat rear surfaces of the blades 12 are adapted to flatly bear on the forward faces of the blades 11. The shiftable blades 12 are initially arranged to have their broad lower portions extend downwardly beyond the cutting edges 19 of the fixed blades 11. The lower portions of the blades 12 are bevelled away at their rear sides to provide lower cutting edges 22. The cutting edges 22 may be straight and may slope downwardly and outwardly. The cutting edges 22 of the shiftable blades 12 may be of substantially the same length as the cutting edges 19. The lower portions of the blades 12 have substantially vertical outer edges 23 which are preferably substantially flush with the outer edges 18 of the

fixed blades 11. The active portions of the blades 12 are preferably hard faces or provided with inserts of hard wear resisting material to be long wearing.

5 Means are provided for guiding the shiftable blades 12 for substantially vertical movement between the active positions where they extend downwardly beyond the fixed blades 11 and the retracted positions where the active parts of the fixed blades are exposed to act on the formation. 10 A vertically elongated slot 24 is provided in each fixed blade 11 and an elongate guide 25 is arranged in each slot. The guides 25 are substantially T-shaped in horizontal cross section having 15 longitudinal ribs or flanges 26 extending along their outer edges. The shiftable blades 12 are provided with longitudinal slots 27 which receive the guides 25 with working clearance. The slots 27 are considerably longer than the guides 25 and extend downwardly beyond the guides when the blades 12 are in their normal or initial active positions. 20 The upper walls of the slots 27 may co-operate with the upper edges of the guides 25 when the blades 12 are in their active positions. The longitudinal ribs or flanges 26 of the guides 25 engage against the forward faces of the blades 12 to retain the blades in engagement with the forward faces of the fixed blades 11. In assembling the tool the blades 12 are arranged against the forward faces of the blades 11 and the guides 25 are inserted into the registering grooves 24 and 27. The guides 25 are then fixed in place by welding the inner edge parts of the guides to the blades 11 at 28.

35 The means 13 operate to hold the blades 12 in the extended operative positions until the cutting parts of the blades 12 are worn away whereupon the means 13 releases to allow the blades 12 to retract or shift upwardly and thus condition the blades 11 for operation. In the embodiment of the invention illustrated in Figs. 1 to 4, inclusive, the means 13 comprise welding or welds 29 connecting or joining the blades 12 with the fixed blades 11. The welds or welding 40 29 are positioned to be worn away through contact with the earth formation at the bottom of the well bore when the active parts of the blades 12 have been worn away. The welds 29 are at the lower edges or cutting edges 19 of the fixed blades 11 and serve to join the rear face portions of the blades 12 to the lower edge portions of the blades 11. The welds 29 may be continuous welds extending along the edges 19, as illustrated, or may be interrupted welds, as desired. The welds 29 are of sufficient strength to dependably 45 resist and transmit the drilling feed pressures to which the blades 11 may be subjected and to dependably resist the jars and shocks to which the tool is subjected when in operation.

50 Figs. 5 and 6 of the drawing illustrate alternative or modified means for releasably holding the blades 12 in their extended active positions which may be used in substitution for the means 13 just described. In the construction shown in Fig. 5 of the drawing the shiftable primary blade 12 has a shoulder 30 on its rear side which engages against the edge 19 of the fixed blade 11. The shoulder 30 may be presented by a continuous elongate ridge on the blade 12 or may constitute the upper surfaces of spaced lugs on the blade. When the lower portion of the blade 12 wears away to the edge 19 the shoulder 30 is worn away and the blade 12 is free to shift upwardly. In the construction shown in Fig. 6 55 of the drawing one or more pins 31 are provided

on the blade 12 and cooperate with the fixed blade 11 to releasably hold the blade 12 in its extended operative position. The pins 31 may be set in sockets 32 in the blade 12 and project from the rear face of the blade to engage upwardly against the edge 19 of the blade 11. The pins 31 are positioned to be worn away or at least weakened to a substantial extent when the active lower part of the blade 12 is worn down. When only partially worn, the pin or pins 31 may shear or break under the feed pressure applied to the bit or the drillers may impose additional pressure on the bit to break the pins 31 if this is deemed necessary. In other cases the pins 31 may merely wear away with the projected part of the blade 12 to finally free the blade 12 for upward retraction.

The well bit preferably includes means for cutting away the core or inner portion of earth formation left standing within the annular series of blades 11 and 12. One or more inner blades 33 are provided on the lower end of the body 10. In the particular case illustrated there are three like inner blades 33 presenting forward faces which lie in substantially vertical radial planes spaced midway between the adjacent blades 11. The rear sides of the inner blades 33 may be bevelled away to provide the blades with suitable cutting edges 34. The active parts of the blades 33 may be hard faced or provided with hard wear resisting material. The inner blades 33 are preferably shorter than the blades 11 and 12, that is, their cutting edges 34 preferably lie in a plane spaced above the active edges of the outer blades 11 and 12. The blades 33 may be of substantial radial extent so that their outer portions overlap the outer blades 11 and 12 in their action on the earth formation. The invention contemplates the provision of shiftable initial cutting blades, similar to the blades 12, for the inner blades 33 to cut away the inner portion of the well bore during the first stages of the drilling operation and to retract or shift upwardly when worn dull. However, in most instances the inner blades 33 are subjected to less wear than the outer blades 11 and it is unnecessary to provide the inner blades with shiftable preliminary blades. It is to be understood that while I have shown the invention embodied in a bit having two sets of cutting parts 11 and 33, the invention is not limited to this application and may be embodied in well drilling tools having one, two or more sets of cutting parts.

Means is provided for flushing the cutting parts of the bit and for producing a suitable turbulence at the bottom of the well bore. Spaced ports 36 may be provided in the lower part of the body 10 to communicate with the fluid opening 15. There may be three ports 36 arranged to discharge downwardly and outwardly from the lower end part of the body. As illustrated there is a port 36 discharging from the body 10 adjacent and in front of each pair of cutter blades 11 and 12. The fluid from the ports 36 effectively flushes the adjacent blades 11 and 12. Downwardly directed ports 37 may be formed in the lower part of the body 10 to join the fluid opening 15. The ports 37 are located to discharge downwardly immediately in front of the inner blades 33. The fluid from the ports 37 washes the blades 33 and impinges against the bottom of the well bore to assist in the drilling action and to provide turbulence.

It is believed that the operation of the bit of the present invention will be readily understood

from the foregoing detailed description. The body 10 is secured to the lower end of the well drilling string and the bit is lowered into the well on the string in the well known manner. When the bit is in position at the bottom of the bore the drilling string is rotated and fed downwardly. The bit is initially in the condition illustrated through the drawing with the active parts of the blades 12 projecting downwardly beyond the fixed blades 11 the projecting cutting blades 12 act on the formation at the bottom of the well to drill or form the major outer portion of the bore and to cut the bore to gauge. The inner blades 33 cut away or break down the formation that may remain within the cut of the outer blades 12. The drilling operation may continue until the active lower portions of the blades 12 are worn away to the welds 29. The blades 12 remain effective in drilling away the earth formation until they are worn to the extent that the welds 29 engage the bottom of the well bore. The welds 29 quickly wear away through engagement with the earth formation. When a weld 29 wears away, the adjacent shiftable blade 12 retracts or shifts upwardly exposing the active lower portion of the adjacent blade 11 so that the blade 11 goes into operation. Up to this point the blades 11 have received practically no wear and their new or unworn cutting edges 19 come into cutting engagement with the earth formation. The rotary motion of the bit in the well bore causes the mud and cuttings to hold the shiftable blades 12 upwardly away from the bottom of the well bore and the blades 11 are free to act effectively. The drilling continues until the blades 11 are dulled or worn to a substantial extent.

The bit embodying the sets of preliminary cutting blades 12 and secondary cutting blades 11 is long-lived, operating substantially twice as long as an ordinary well bit. The blades 12 automatically retract when worn away and the blades 11 are automatically brought into operation at this time without the necessity of suspending the rotary drilling operation or of withdrawing the bit from the well. Following the operation of the bit and its withdrawal from the well the blades 12 may be removed and the blades 11 may be built up or reconditioned. New blades 12 or reconditioned blades 12 may be assembled on the reconditioned bit. The bit is easy to repair or recondition.

Having described only typical preferred forms and applications of my invention, I do not wish to be limited or restricted to the specific details herein set forth, but wish to reserve to myself any variations or modifications that may appear to those skilled in the art or fall within the scope of the following claims:

Having described my invention, I claim:

1. A well drilling tool comprising a body, a projecting cutting part on the body, a shiftable cutting part, and means for holding the shiftable cutting part in a position where it extends beyond the first named cutting part and releasable to allow retraction of the shiftable cutting part from the cutting position when the shiftable cutting part is worn to given extent.

2. A well bit comprising a body, a part rigid with the body and projecting therefrom, said part having a cutting edge, a cutting member shiftable on said part, and means at said edge for holding the cutting member in a position where it extends beyond said cutting edge to act on the earth formation and releasable to allow

retraction of the member when the member is worn away to said edge.

3. A well bit comprising a body, a cutting part rigid with and projecting from the body, a cutting member shiftable on said part, and means securing the member to said part to have an active cutting portion project beyond said part and releasable to permit retraction of the member when said portion is worn away.

4. A well drilling bit comprising a bit body, 10 a blade rigid with the body and projecting downwardly therefrom to present a lower cutting edge, a shiftable blade adapted to project downwardly beyond the rigid blade to act on the bottom of the well and to prevent said edge from engaging the well bottom, and means for holding the shiftable blade in the position where it projects beyond the rigid blade and releasable through engagement with the well bottom when the shiftable blade has worn a given amount to allow upward 20 retraction of the shiftable blade so that said edge is exposed to act on the well bottom.

5. A well drilling bit comprising a bit body, a blade rigid with the body and projecting downwardly therefrom to present a lower cutting edge, 25 a shiftable blade adapted to project downwardly beyond the rigid blade to act on the bottom of the well and to prevent said edge from engaging the well bottom, and welding securing the shiftable blade to the rigid blade to project downwardly beyond the rigid blade, the welding being positioned to be worn away and released when the shiftable blade has worn to given point.

6. A well drilling bit comprising a bit body, 35 a blade rigid with the body and projecting downwardly therefrom to present a lower cutting edge, a preliminary cutting blade shiftable vertically on the rigid blade, and means for holding the preliminary blade against upward movement in a position where it projects downwardly beyond said edge to have preliminary cutting engagement with the bottom of the well, said means including a part on the shiftable blade engaging upwardly against the rigid blade adapted to be worn away through engagement with the bottom of the well when the preliminary blade is worn to a given point.

7. A well drilling bit comprising a bit body, a blade rigid with the body and projecting downwardly therefrom to present a lower cutting edge, a preliminary cutting blade shiftable vertically on the rigid blade, and means for holding the preliminary blade against upward movement in a position where it projects downwardly beyond said edge to have preliminary cutting engagement with the bottom of the well, said means including a part on the shiftable blade engaging upwardly against said cutting edge and adapted to be drilled away by contact with the bottom of the well when the preliminary blade is worn away to said cutting edge.

8. In a well bit having a bit body, the combination of a projecting cutting blade rigid with the body, the cutting blade presenting a cutting edge, a shiftable cutting blade, means supporting the shiftable blade on the first named blade for movement between an active position where it projects beyond said edge to act on the earth formation and a retracted position where it exposes said edge for action on the earth formation, and an abutment on one of the blades cooperating with the other blade to hold the shiftable blade in said active position and formed to be drilled away through contact with the earth formation 70 75

when the shiftable blade is worn to a given extent to allow the shiftable blade to move to the retracted position.

9. In a well bit having a bit body, the combination of a projecting cutting blade rigid with the body, the cutting blade presenting a cutting edge, a shiftable cutting blade, means supporting the shiftable blade on the first named blade for movement between an active position where it projects beyond said edge to act on the earth formation and a retracted position where it exposes said edge for action on the earth formation, and welding joining the two blades at said edge to hold the shiftable blade in the active position and adapted to be worn away through contact with the earth formation when the shiftable blade is worn to a given extent to free the shiftable blade for movement to the retracted position.

10. In a well bit having a bit body, the combination of a projecting cutting blade rigid with the body, the cutting blade presenting a cutting edge, a shiftable cutting blade, means supporting the shiftable blade on the first named blade for movement between an active position where it projects beyond said edge to act on the earth formation and a retracted position where it exposes said edge for action on the earth formation, and a pin on the shiftable blade cooperating with said cutting edge to hold the shiftable blade in the active position and adapted to be worn away or broken to free the shiftable blade for movement to the retracted position when the shiftable blade is worn away to said edge.

11. A well drilling bit comprising a body for connection with a rotary well drilling string, a plurality of spaced cutting blades projecting downwardly from the body, a shiftable blade on each of the first named blades, means for guiding the shiftable blades between active positions where they project downwardly beyond the first named blades and retracted positions where they expose the first named blades for action, and means attaching the shiftable blades to their respective first named blades to hold the shiftable blades in their active positions and formed to be worn away through engagement with the earth formation to free the shiftable blade for movement to the retracted positions when the shiftable blades are worn to given extent.

12. A well drilling bit comprising a body for connection with a rotary well drilling string, a plurality of spaced cutting blades projecting downwardly from the body, a shiftable blade on each of the first named blades, the shiftable blades having longitudinal slots, guides on the first named blades extending into the slots and guiding the shiftable blades between active positions where they project beyond the first named blades and retracted positions where they expose the first named blades for action, and welds securing the shiftable blades to their respective first named blades with the shiftable blades in their active positions and adapted to be worn away to free the shiftable blades for movement to the retracted positions when the shiftable blades have been worn away to the lower edges of the first named blades.

13. A well drilling bit comprising a body for connection with a rotary well drilling string, a plurality of spaced cutting blades projecting downwardly from the body, a shiftable blade on each of the first named blades, the shiftable blades having longitudinal slots, guides on the

first named blades extending into the slots and guiding the shiftable blades between active positions where they project beyond the first named blades and retracted positions where they expose the first named blades for action, flanges on the guides cooperating with the shiftable blades to hold them against the forward faces of the first named blades, and welds securing the shiftable

blades to their respective first named blades with the shiftable blades in their active positions and adapted to be worn away to free the shiftable blades for movement to the retracted positions 5 when the shiftable blades have been worn away to the lower edges of the first named blades.

MAX A. NEWTON.
